UNITED STATES PATENT OFFICE.

GOODMAN BURSETOWN, OF HOUSTON, TEXAS.

DESIGN FOR AN ASH TRAY.

Application filed December 20, 1923. Serial No. 8,105. Term of patent 3½ years.

To all whom it may concern:

Be it known that I, GOODMAN BURSETOWN, a citizen of the United States, residing at Houston, in the county of Harris and State of Texas, have invented a new, original, and ornamental Design for Ash Trays, of which the following is a specification, reference being had to the accompanying drawings, forming part hereof.

In the drawings, Figure 1 is a perspective view of the design, showing one side and Figure 2 illustrates the opposite side of the design.

I claim;

The ornamental design for an ash tray as shown.

GOODMAN BURSETOWN.
